UNITED STATES PATENT OFFICE.

ERNEST BERNARD GUSTAFSON, OF MINNEAPOLIS, MINNESOTA.

FOLDING UMBRELLA.

Application filed July 17, 1924. Serial No. 726,539.

To all whom it may concern:

Be it known that I, ERNEST B. GUSTAFSON, a citizen of the United States, residing at Minneapolis, in the county of Hennepin and 5 State of Minnesota, have invented certain new and useful Improvements in Folding Umbrellas, of which the following is a specification.

The present invention relates to an umbrella adapted to be collapsed to take up very little room, particularly in the length direction so that it may conveniently be carried about in a small hand bag or in a coat pocket. This is made possible by 10 constructing the handle telescopically and providing joints in several places for the ribs supported by reinforcing braces which also 15 fold when the umbrella is collapsed.

An ordinary umbrella is rather unhandy 20 to carry about when not in use and particularly the length of the same prevents it from being carried in a small bag, whereas the umbrella forming the subject-matter of the present invention can be easily carried 25 without inconvenience.

By properly arranging the joints of the ribs and the braces beneath the same, the umbrella becomes very rigid when open.

When open the umbrella handle is of such 30 a size that it is very comfortable to carry.

In the accompanying drawings, one embodiment of the invention is illustrated, and Figure 1 is a bottom plan view of the umbrella open;

Figure 2 is a side elevation partly in section of the umbrella open;

Figure 3 is a fragmentary side elevation of the umbrella partly closed;

Figure 4 is a vertical section of the umbrella very nearly closed;

Figure 5 shows the umbrella in folded position;

Figure 6 is a section along line 6—6 of Figure 2;

Figure 7 is a section along line 7—7 of the same figure;

Figure 8 is a fragmentary section along line 8—8 of Figure 2;

Figure 9 is a top plan view of one of the joints for the ribs;

Figure 10 is a side elevation of Figure 9;

Figure 11 is a fragmentary side elevation of another one of the joints;

Figure 12 is a top plan view of Figure 11;

Figure 13 is a side elevation of still another of the rib joints,

Figure 14 is a section along line 14—14 of Figure 13;

Figure 15 is a side elevation of one of the braces, and

Figure 16 is a section along line 16—16 of Figure 2.

Each main rib 20 consists of five rib elements 21, 22, 23, 24 and 25. The innermost rib element 21 is hinged, as at 26, to a top circular disc 27 to which all the ribs 20 are hinged. The hinge is produced in the usual manner by passing a wire 28 through the ribs and placing the same in an annular groove 29 furnished in the disc, see Figures 4 and 6. The outer end of the rib element 21 is hinged, as at 30, to the second rib element 22 which in turn is hinged, as at 31, to the third rib element 23. The latter has a joint 32 connecting it with the fourth element 24. The ribs are of the usual U-shape or channel cross section and the joint 30, best seen in Figures 9 and 10, consist of several leaves 34 riveted to the respective ends of the rib elements 21 and 22 between the side flanges of the channels and connected by means of a pivot or rivet 35 and in such a manner that the elements fold together as indicated in Figures 3 and 10 with their outer faces nearest each other.

A little over half way down from the upper end of the rib element 21 is shown another hinge or joint 36 riveted thereto and adapted to engage a brace element 37 which in turn is hinged, as at 38, to a lower brace element 39. The exact distance between the joints 36 and 30 is equal to half the length of the rib element 22 plus the added thickness of the disc 27 and a second disc 40, the latter being the next in order under the top disc 27.

The rib element 21 is retained in position by the brace elements 37 and 39 when straightened out and the said rib element drops down when these elements are collapsed outwardly. When the umbrella is open the second rib element 22 is held in open position supported by the first rib element 21 and the brace elements 37 and 39 while said rib element cannot drop down below its position in alinement with the

first rib element 21 on account of the one-way joint 30, as indicated in Figure 2 of the drawings.

The rib elements 22, 23 and 24 are all of the same length which is the common length of most of the parts and is the actual length of the umbrella when folded. For an ordinary umbrella of this character these last named rib elements will be five inches in length so that the total length of the umbrella folded will be five inches. The rib elements 22 and 23 fold together with the rib element 21 in zig zag fashion, as best seen in Figure 3. The joint 31 being a one-way joint is kept down by the stretched cloth or silk covering when the umbrella is open. The joint 32 between the rib elements 23 and 24 is kept in open position by the brace elements 41, 42, 43 and 44 which together form a complete brace rod when open. This brace is also hinged at the joint 32 which permits the rib element 24 to fold upwardly against the rib element 23 and the joint 33 is like the joint 30 permitting the folding upwardly of the outermost rib element 25 as regards the nearest rib element 24, as seen in Figure 3 of the drawings. When the umbrella is open, the outermost rib element 25 is kept down by the pressure from the cloth or silk cover of the umbrella so that it makes a practically straight line with the rib element 24. The rib element 25 is slightly shorter than the rib element 24 in order to permit the same to be folded between the rib elements 23 and 24.

The brace element 41 is of the same length as the rib elements 22, 23 and 24 and can swing freely in both directions in the hinge joint 32, whereas this joint only permits the movement in one direction between the rib elements 23 and 24, as has already been described. The joint 45 between the brace elements 41 and 42 is similar to the joints 30 and 33, that is to say, it permits the folding together of the brace elements 41 and 42 but keeps these elements in stiff connection when in alinement with each other. In folding, the brace elements 41 and 42 swing outside of the rib elements 24 and 25. Reference numeral 43 represents a short link connecting the brace elements 42 and 44 having a one-way joint 46, see particularly Figures 11 and 12, and a similar joint 47 connecting it to the innermost brace element 44. The main purpose of furnishing the short link 43 is to assist in the folding of the umbrella and it is also needed to make up the total length required of the brace formed by the elements 41, 42, 43 and 44. It will be seen that the elements 41 and 42, as already stated, swing around to the outside of the rib elements 23, 24 and 25 when the umbrella is folded, and that the inner ends of the rib elements fold together with a rod 48 when the umbrella is col-

lapsed. This rod is also hinged at the joint 47 at its outer end and at its inner end to the second circular disc 40 while the inner end of the brace element 44 is hinged, as at 49, to the brace element 39 which in turn has hinge connection, as at 50, with a third circular sliding disc 51.

The brace element 44 has the same length as the brace element 39 measured from the joint 38 to the joint 49 and accordingly slightly less than the brace elements 41 and 42. In folding the umbrella the hinge joint 38 moves in downward direction to the hinge joint 47 and both together move downwardly when the sliding disc 51 is pushed upwardly. The brace rod 48 is pivotally secured in the second circular disc 40 by means of a wire 52 which goes through a small opening provided at the end of the rod. It is evident that this inner end of the brace rod 48 moves upwardly with the disc 40 and its opposite end downwardly when the umbrella is being folded. The main function of this brace rod is to stiffen the brace formed by the elements 41, 42, 43 and 44 when the umbrella is open. The length is the same as the other brace elements plus the thickness of the disc 40.

The brace element 39 is similar to the rest of the brace elements and has the same length as the elements 41 and 42. It is hinged, as at 38, to the short brace element 37, this joint 38 permitting only outward folding of each brace element. The inner end of the brace element 39 is pivotally secured to the sliding disc 51 by means of a wire engaging in a suitable opening at the end of said brace element. The upper brace element 37 has a length equal to about half the length of the ordinary brace elements, or equal to the distance from the joint 36 to the joint 30.

As the umbrella folds the hinge joint 38 moves in the direction of the joint 30 and the lower end of the brace element 39 moves up together with the sliding disc 51 as the said disc together with the disc 40 is moved up against the disc 27. On account of its construction the joint 38 naturally swings in outward direction, but when the umbrella is open the brace formed by the elements 37 and 39 is straight and the pressure of the rib element 21 at the upper end of the brace will tend to keep it in this position. When folded the same pressure will also tend to keep the brace against the central stem.

The stem of the umbrella is composed of seven telescopic parts 55, 56, 57, 58, 59, 60 and 61, the innermost rod 55 extends from the top of the umbrella downwards and is surrounded by a tubular stem portion 56 forming an integral part with the uppermost circular disc 27 or being united therewith in any suitable manner. Outside of the tubular portion 56 is positioned the

tubular portion 57 to which the second circular disc 40 is similarly united. Similarly the tubular portions 58, 59 and 60 are telescopically arranged one outside another, the 5 tubular portion 58 being provided at its top with the circular disc 51 while the tubular portions 59 and 60 each have similar discs 63 and 64, respectively. The outermost tubular portion 61 has a collar 54 and terminates at its bottom end with a mushroom shaped handle knob 62. Concentrically arranged on this handle knob is provided a series of annular steps 65 each step being of the same diameter as the corresponding one 10 of the tubular portions. In this manner the lower ends of these tubular portions fit snugly around the lower end of the stem when the umbrella is in closed position. The cylindrical portions of the stem all fit 15 snugly one within the other, permitting easy sliding between them.

The tubular portion 56 extends above the disc 27 as best seen in Figure 4 and is provided with a longitudinal slot 66 on one side 20 thereof adapted to engage a spring latch 67 provided inside of the tubular portion 55, the latch being situated at the lower end of this tubular portion and adapted to project through a small slot 68 therein when the 25 said slot registers with the slot 66 in the tubular portion 56. This spring latch 67 operates in the same manner as similar latches provided on ordinary umbrellas to keep them in open position and has to be 30 pressed in through the slot 66 to permit the sliding up and down of the innermost rod 55. This spring latch serves the purpose of locking the rod 55 either in extended or pushed in position. At its upper end this 35 rod 55 terminates with a small ball or finger grip 69 furnished for the purpose of preventing the rod to slip down into the next tubular portion 56 and also to draw out this rod.

40 The discs 27, 40, 51, 63, 64 and the collar 54 are all similar and have flat top and bottom faces and a groove around their edges for hinge wires, as already described with regard to the discs 27 and 40. These 45 discs are recessed or notched around their edges to receive the ends of the rib elements or brace elements, as the case may be. These discs are all diminishing in diameter from the uppermost one 27 to the collar 54 which 50 is lowermost for the purpose of permitting the close folding of the rib and brace elements. The disc 27 is provided with notches 70 of the same number as the number of ribs 20 used in the construction of 55 the umbrella, six being shown in the drawings (see Figure 6), but this number may naturally be increased to eight or more. Beside these rib notches the disc is also provided with four other notches 71 and 53 60 for intermediary braces 72 and 81.

The second disc 40 has the same number of notches as the disc 27, that is to say, in this case notches 73, six in number, correspond to the rib notches 70 in the upper disc 27 and are adapted to receive the inner ends 70 of the straight brace rods 48, while two of the four notches 75 are adapted to receive the ends of the braces 72 and the other two notches 75 the braces 74.

The next circular disc 51 is also provided with notches in its side edge, two more in number than the other two discs and six of these notches are adapted to receive the lower ends of the brace elements 39 and four of the other six notches are provided to accommodate the lower ends of the braces 74 as well as the upper ends of the braces 77 while the remaining two notches engage the lower ends of the braces 81.

The next circular disc 63 has only four notches, two of which are adapted to engage the lower ends of the braces 77, while the other two notches take the upper ends of other braces 78. Similarly, the disc 64 has four notches, two of which engage the lower ends of the braces 78 and the other two notches engage the upper ends of braces 79. Finally, the collar 54 has two notches adapted to receive the lower ends of the braces 79.

It should be noted that the braces 72, 74, 77, 78, 79 and 81 each consist of two short links hinged together in the middle and adapted to fold away from the stem of the umbrella. The main purpose of these longitudinal braces is to determine the distances between the several discs and keep them in place when the umbrella is open and in this manner stiffen the main stem of the umbrella. Each of these braces have their upper links slightly longer than the lower ones to permit easy folding and the joints are made as small as possible and are of the same type as the hinges 30 for the ribs. These braces are also hinged in their respective discs by means of wires placed in the annular grooves around the edges thereof. The uppermost brace 72 is shorter than the others, in fact less than half the length of the other braces and these short braces will remain slightly bent when the umbrella is open, because the distance between the discs 27 and 40 is determined by the main braces 81 which engage in the notches of the uppermost disc 27 and the third disc 51.

In determining the distance between the discs 27, 40, 51, 63, 64 and collar 54 it should be borne in mind that each brace should be as much shorter, than the brace above, as the thickness of the corresponding disc. Surrounding the telescopic stem is furnished a tubular handle comprising five sections, 82, 83, 84, 85 and 86 all tapering downwardly. The taper of these sections is

130

such that the lower end of an outer section is adapted to grip tightly the upper end of the next inner section when the umbrella is open. When the umbrella is closed all the lower ends of the sections rest on the knob 62, as best seen in Figure 4. Of these sections, the section 82 is smallest in diameter and slightly larger than the stem portion 61, the other sections increasing in diameter in their order of assembly. The outermost section 86 is shorter than the others in order to provide more room to permit the braces 79 to fall over the same when the umbrella is closed. This outermost section 86 has still another function, namely to fold the six braces formed by the elements 37 and 39 together as well as the braces 81. When the section 86 is pushed up a catch 87 secured on the disc 51 engages in a suitable slit 88 provided in the side of the said section, as best seen in Figure 8. The catch 87 is preferably secured on the bottom side of the disc 51 and adapted to swing inwardly when pressed by the operator's finger. The catch 87 is provided with a hook or finger 89 which is adapted to slide along the upper surface of the disc 51. Around the upper edge of the section 86 is provided a series of recesses 90 which are adapted to engage the folded braces when the section is locked by the catch 87 and the umbrella folded.

With regard to the hinge joints used for the ribs and braces it should be noted that they have been constructed especially for this folding umbrella. The construction of these joints is of great importance during the operation of the folding umbrella and without such construction the invention would not be a success. The main feature and advantage of these joints is that they allow the parts to open until the ribs or braces are in alinement and no further, and being constructed of double leaves as indicated in Figures 12 and 14, they fit smoothly together and there can only be a movement in the plane of the ribs or braces and no side movement thereof. Referring particularly to Figs. 11 and 12, it will be noted that the under side of the hinge blades are offset to provide shoulders 91 which interengage when the braces or ribs are unfolded, that is to say, in alined position.

To close the umbrella the first thing to do is to release the catch 87 and pull down the telescopic sections 82, 83, 84, 85 and 86. Next the tubular portion 61 is pushed up until all the parts of the main stem are against the disc 51 and with the said disc pushed in slightly in order to release the joints, whereupon the catch 67 is released and the finger grip 69 is pushed in. The outermost rib elements 25 are thereupon folded upwardly over the rib elements 24 and the said elements together folded at the joints 32 against the next rib element 23.

The joint 47 is pulled out slightly and the tubular portion 61 pushed up as far as it will go until the discs are in contact with each other. The rib sections 21, 22 and 23 are now squeezed together and the brace elements 41 and 42 folded outside of the other parts. It should, of course, be understood that the cloth or silk cover 92 which is secured on the outer side of the rib elements 22, 23, 24 and 25 becomes folded in between said elements, see Fig. 5.

In order to open the umbrella, the operator takes hold of the finger grip 69 with one hand and grasps firmly the knob 62 with his other hand. The rod 55 is then drawn out until the catch 67 engages in the slot 66 and the pull is continued so that the stem formed by the stem portions 55, 56, 57, 58, 59, 60 and 61 is extended to its full length. Thereupon the operator should take hold of the joints 45 and pull them down and then pull the joints 33 outwardly until they are open. This will straighten out the braces along the main stem and properly locate the discs with relation to each other. Lastly, the section 86 is pushed upwards along the stem until the catch 87 engages in the slit 88, the section 86 simultaneously drawing out the other sections with it and the umbrella is now ready for use.

Having thus described the invention, what is claimed as new is:

1. A collapsible umbrella, comprising a plurality of tubular stem portions having telescopic relation with each other, a disc for each of said stem sections firmly united with the upper ends thereof, a plurality of ribs having hinge connection with the uppermost of said discs, braces having hinge connection with the respective ribs and with another of said discs, and means for rigidly retaining the discs separated when the umbrella is in open position, said means including jointed braces having hinge connection with adjacently situated discs. 100

2. A collapsible umbrella, comprising a plurality of tubular stem portions having telescopic relation with each other, a disc for each of said stem sections firmly united with the upper ends thereof, a plurality of ribs having hinge connections with the uppermost of said discs, braces having hinge connections with the respective ribs and with another of said discs, and means for rigidly retaining the discs separated when the umbrella is in open position, said means including jointed braces having hinge connection with adjacently situated discs, the joints of said second braces being adapted to fold outwardly and downwardly from said discs when the umbrella is collapsed. 115

3. A collapsible umbrella, comprising a plurality of tubular stem portions having telescopic relation with each other, a disc for each of said stem sections firmly united 130

- with the upper ends thereof, a plurality of ribs having hinge connection with the uppermost of said discs, braces having hinge connection with the respective ribs and with another of said discs, means for rigidly retaining the discs separated when the umbrella is in open position, said means including jointed braces having hinge connection with adjacently situated discs, the joints of said second braces being adapted to fold outwardly and downwardly from said discs when the umbrella is collapsed, and a tubular handle surrounding said stem. 5

4. A collapsible umbrella, comprising a plurality of tubular stem portions having telescopic relation with each other, a disc for each of said stem sections firmly united with the upper ends thereof, a plurality of ribs having hinge connection with the uppermost of said discs, braces having hinge connection with the respective ribs and with another of said discs, means for rigidly retaining the discs separated when the umbrella is in open position, said means including jointed braces having hinge connection with adjacently situated discs, the joints of said second braces being adapted to fold outwardly and downwardly from said discs when the umbrella is collapsed, and a tubular handle surrounding said stem. 10

- lower section when the handle is in extended position, a knob at the lower end of the outermost of said stem portions forming an abutment for all of said sections when the umbrella is collapsed, and a gripping member slidably engaging the innermost of said stem portions and being provided with a spring latch adapted to engage with the uppermost of said discs to cooperate in extending said stem.
9. A collapsible umbrella, comprising a plurality of tubular stem portions having telescopic relation with each other, a disc for each of said stem sections firmly united with the upper ends thereof, a plurality of ribs having hinge connection with the uppermost of said discs, braces having hinge connection with the respective ribs and with another of said discs, means for rigidly retaining the discs separated when the umbrella is in open position, said means including jointed braces having hinge connection with adjacently situated discs, the joints of said second braces being adapted to fold outwardly and downwardly from said discs when the umbrella is collapsed, a tubular handle surrounding said stem, said handle tapering from its upper to its lower end and comprising a plurality of sections, the lower end of each of said sections adapted to grip tightly the upper end of an adjacent lower section when the handle is in extended position, a knob at the lower end of the outermost of said stem portions forming an abutment for all of said sections when the umbrella is collapsed, a catch provided on the lowermost of said discs adapted to lock the outermost of said sections in position, and a gripping member slidably engaging the innermost of said stem portions and being provided with a spring latch adapted to engage with the uppermost of said discs to cooperate in extending said stem.
10. A collapsible umbrella, comprising a plurality of tubular stem portions having telescopic relation with each other, a disc for each of said stem sections firmly united with the upper ends thereof, a plurality of ribs having hinge connection with the uppermost of said discs, and braces having hinge connection with the respective ribs and with another of said discs, each of said ribs including a plurality of elements and one-way joints connecting the meeting ends of adjacent elements, said joints being adapted to permit the folding of the adjacent ones of said elements in one direction only and to hold the elements in alinement when extended.
11. A collapsible umbrella, comprising a plurality of tubular stem portions having telescopic relation with each other, a disc for each of said stem sections firmly united with the upper ends thereof, a plurality of ribs having hinge connection with the uppermost of said discs, and braces having hinge connection with the respective ribs and with another of said discs, each of said ribs including a plurality of elements and one-way joints connecting the meeting ends of adjacent elements, said joints adapted to hold the elements in alinement when extended and permitting the folding of all of said elements but the outermost one in zig-zag formation, said outermost element folding upwardly against the adjacent element.
12. A collapsible umbrella, comprising a plurality of tubular stem portions having telescopic relation with each other, a disc for each of said stem sections firmly united with the upper ends thereof, a plurality of ribs having hinge connection with the uppermost of said discs and each consisting of hingedly connected rib elements, a short and a long brace for each of said ribs having hinge connection with another of said discs, the short brace having hinge connection with the innermost of said rib elements and the long brace having hinge connection with the third of said elements.
13. A collapsible umbrella, comprising a plurality of tubular stem portions having telescopic relation with each other, a disc for each of said stem sections firmly united with the upper ends thereof, a plurality of ribs having hinge connection with the uppermost of said discs and each consisting of hingedly connected rib elements, a short and a long brace for each of said ribs having hinge connection with another of said discs, the short brace having hinge connection with the innermost of said rib elements and the long brace having hinge connection with the third of said elements, said short brace comprising a short link and a long link having an outwardly breaking joint connecting it with said short link, said short link being hinged between the ends of the innermost rib element.
14. A collapsible umbrella, comprising a plurality of tubular stem portions having telescopic relation with each other, a disc for each of said stem sections firmly united with the upper ends thereof, a plurality of ribs having hinge connection with the uppermost of said discs and each consisting of hingedly connected rib elements, a short and a long brace for each of said ribs having hinge connection with another of said discs, the short brace having hinge connection with the innermost of said rib elements and the long brace having hinge connection with the third of said elements, said short brace comprising a short link and a long link having an outwardly breaking joint connecting it with said short link, said short link being hinged between the ends of the innermost rib element, said long brace comprising a plurality of links connected by joints.

adapted to break outwardly and the outermost of said links being hinged in the joint of said third rib element.

15. A collapsible umbrella, comprising a plurality of tubular stem portions having telescopic relation with each other, a disc for each of said stem portions firmly united with the upper ends thereof, a plurality of ribs having hinge connection with the uppermost of said discs and each consisting of hingedly connected rib elements, a short and a long brace for each of said ribs having hinge connection with the third of said discs, the short brace having hinge connection with the innermost of said rib elements and the long brace having hinge connection with another of said elements, said short brace comprising a short link and a long link having an outwardly breaking joint connecting it with said short link, said short link being hinged between the ends of the innermost rib element, said long brace comprising a plurality of links connected by joints adapted to break outwardly and the outermost of said links being hinged in the joint of said third rib element, means for rigidly retaining the discs separated when the umbrella is in open position, said means including jointed braces having hinge connection with adjacently situated discs, the joints of said second braces being adapted to fold outwardly and downwardly from said discs when the umbrella is collapsed, a tubular handle surrounding said stem, said handle tapering from its upper to its lower end, and comprising a plurality of sections, the lower end of each of said sections adapted to grip tightly the upper end of an adjacent lower section when the handle is in extended position, a knob at the lower end of the outermost of said stem portions forming an abutment for all of said sections when the umbrella is collapsed, a catch provided on the lowermost of said discs adapted to lock the outermost of said sections in position, a gripping member slidably engaging the innermost of said stem portions and being provided with a spring latch adapted to engage with the uppermost of said discs to cooperate in extending said stem, and a stiff rod hinged at its inner end to the second of said discs and at its outer end to the joint at the outer end of the innermost of said long brace links.

16. A collapsible umbrella, comprising a plurality of tubular stem portions having telescopic relation with each other, a disc for each of said stem portions firmly united with the upper ends thereof, a plurality of ribs having hinge connection with the uppermost of said discs and each consisting of hingedly connected rib elements, a short and a long brace for each of said ribs having hinge connection with the third of said discs, the short brace having hinge connection with the innermost of said rib elements and

the long brace having hinge connection with the third of said elements, said short brace comprising a short link and a long link having an outwardly breaking joint connecting it with said short link, said short link being hinged between the ends of the innermost rib element, said long brace comprising a plurality of links connected by joints adapted to break outwardly and the outermost of said links being hinged in the joint of said third rib element, means for rigidly retaining the discs separated when the umbrella is in open position, said means including jointed braces having hinge connection with adjacently situated discs, the joints of said second braces being adapted to fold outwardly and downwardly from said discs when the umbrella is collapsed, a tubular handle surrounding said stem, said handle tapering from its upper to its lower end, and comprising a plurality of sections, the lower end of each of said sections adapted to grip tightly the upper end of an adjacent lower section when the handle is in extended position, a knob at the lower end of the outermost of said stem portions forming an abutment for all of said sections when the umbrella is collapsed, a catch provided on the lowermost of said discs adapted to lock the outermost of said sections in position, a gripping member slidably engaging the innermost of said stem portions and being provided with a spring latch adapted to engage with the uppermost of said discs to cooperate in extending said stem, and a stiff rod hinged at its inner end to the second of said discs and at its outer end to the joint at the outer end of the innermost of said long brace links.

In testimony whereof I affix my signature.

ERNEST BERNARD GUSTAFSON. [L. S.]
